UNITED STATES PATENT OFFICE.

RECTOR E. LAND, OF MOUNT WASHINGTON, MISSOURI.

RAILWAY BLOCK-SIGNAL SYSTEM.

SPECIFICATION forming part of Letters Patent No. 778,418, dated December 27, 1904.

Application filed April 25, 1904. Serial No. 204,783.

To all whom it may concern:

Be it known that I, RECTOR E. LAND, a citizen of the United States, residing at Mount Washington, in the county of Jackson and State of Missouri, have invented new and useful Improvements in Railway Block-Signal Systems, of which the following is a specification.

My invention relates to improvements in railway block-signal systems.

The object of my invention is to provide a system in which a train passing over the track will actuate electric signals in advance and to the rear of the train.

In my system the track is divided into blocks insulated from each other, opposite rails of each block being mounted upon wooden ties, and thus insulated from each other against the passage of currents of comparatively low voltage. Branch conductors connect, respectively, opposite rails of each block with two feed-wires, which are connected, respectively, with a suitable electrical generator. In some of the branch conductors of each block are located electrically-actuated signaling devices, such as electric lamps.

My invention provides, further, a series of electrical signaling devices disposed two adjacent each end of each block, each of said two signaling devices being connected, respectively, with one of the feed-conductors and with one of the rails of each block, each of said two signaling devices being disposed in advance of the block to which it is connected.

My invention provides, further, a novel signaling mechanism for application to switches running from a main line of the track.

Other novel features are hereinafter fully described and claimed.

The accompanying drawing represents a diagrammatic view of a railroad-track having a switch and provided with the signaling system of my invention.

1 denotes the ties upon which the rails are laid; 2 and 3, the opposite rails of block A; 4 and 5, the opposite rails of block B; 6 and 7, the opposite rails of block C, and 8 and 9 the opposite rails of block D. Like sets of rails of opposite blocks are insulated from the

rails of adjacent blocks by the insulation E. As electric currents of comparatively low voltage are employed, the ground and the ties 1 practically insulate the opposite rails of a block from each other. Disposed parallel with and adjacent the track are two feed-conductors F and G, connected, respectively, by conductors 10 and 11 with a suitable generator H. The rails 3, 5, 7, and 9 of the different blocks are connected with the feed-conductor G by conductors 12, 13, 14, 15, 16, and 17, respectively. To the rails 2, 4, 6, and 8 are connected, respectively, the conductors 18, 19, 20, 21, 22, and 23. The opposite end of each of said conductors 18, 19, 20, 21, 22, and 23 is bifurcated and connected with the feed-conductor F.

24 denotes the two arms of the bifurcated conductor 18; 25, the two arms of the conductor 19; 26, the arms of the conductor 20; 27, 70 the arms of the conductor 21; 28, the arms of the conductor 22, and 29 the arms of the conductor 23.

30 and 31 denote two electrically-actuated signaling devices, such as two incandescent 75 electric lamps, located, respectively, in the two arms 24. 32 and 33 denote similar signals located, respectively, in the arms 25. 34 and 35, 36 and 37, 38 and 39, 40 and 41 indicate similar signals disposed, respectively, in 80 the arms 26, 27, 28, and 29.

The lamps 30 and 31 are located in advance of the block A, to the rails 2 of which they are electrically connected. The lamp 30 is located adjacent the points where the blocks 85 A and B meet, while the lamp 31 is located farther ahead from the said meeting-point. The lamps 32 and 33 are similarly located respecting the left end of the block B. The lamps 34 and 35 are also similarly located respecting the right end of the block B. In a like manner the lamps 36 and 37, 38 and 39, 40 and 41 are similarly located relative to the adjacent ends of the block, to the rails of which they are electrically connected. Between the lamps 30 and 32, 34 and 36, 38 and 40 are inserted, respectively, transverse light-shields 42, 43, and 44. These shields are disposed substantially in transverse planes corresponding, respectively, to the meeting- 100

points of the blocks A, B, C, and D. The said shields are so located as to prevent the lamps between which they are inserted being seen from the blocks to which the said lamps 5 are respectively connected.

The switch-track is denoted by I, 45 denoting the rails on one side of the track, and 46, 47, and 48 denoting the rails upon the opposite side of the switch-track.

10 J denotes insulation inserted at each end of the rail 47.

A conductor 49 connects the rails 46 and 48 around the rail 47, the said conductor being disposed in a conduit 50, crossing under the 15 rail 5 of block B. The rail 47 crosses the said rail 5. The rail 46 is connected to a switch-bar comprising two transverse members 51 and 52, connected with each other by means of insulation K. The rail 46 connects 20 with the member 51 and the rail 45 with the member 52, the members 51 and 52 being connected, respectively, with the rails 4 and 5 of the block B.

In operating my system a car on the block 25 A will through its wheels and axles electrically connect the rails 2 and 3, and a current passing from the generator H through conductors 11, G, 12, car wheel and axles, (not shown,) rail 3, rail 2, conductor 18 and its arms 24, 30 and lamps 30 and 31, conductor F and conductor 10 will illuminate the lamps 30 and 31, thus giving warning to a train passing on block B toward block A. A train on the track in block B will connect the rails 4 and 35 5 by means of the wheels and axles of the cars forming the train. The current will then traverse the following circuit, beginning at generator H and passing through conductors 11, G, 13, and 14, rails 5, car wheels and 40 axles to rails 4, thence through conductors 19 and 20, lamps 32, 33, 34, and 35, arms 25 and 26, and conductors F and 10 to the generator H. The lamps 32, 33, 34, and 35 will thus be lighted and warn trains in blocks A and C 45 that a train occupies the track in block B. The shields 42, 43, and 44 are provided so that the engineer of a train will not see the adjacent signal that his own train lights, and so confuse it with the lamps lighted by a train 50 in the block next adjoining. As a train leaves a block it will cause the lights to the advance and in the rear of it in the next block to be lighted. A train approaching the main track on the switch-track 1 will cause the 55 lamps 33 and 32 to be lighted, the current passing from generator H through conductors 11 and G, conductor 13, rail 5, rail 45 by way of member 52, thence by the wheels and axles of the train (not shown) to rail 48, conductor 49, rail 46, member 51, rail 4, thence by conductors 19 and 20, lamps 32 and 33, 34 and 35, arms 25 and 26, and conductors F and 10 to generator H, thus warning trains at

each side of the junction-point of the switch and main-line tracks.

65

It will be noted that with the use of my invention a train at any place in a block will at all times have a danger-signal in advance and to the rear of it. The electric generators H may be located along the track at whatever 70 distance apart may be desired. Any suitable electrically-actuated signal may be utilized, visible ones being those preferred. At night electric lamps may be utilized and by day any suitable signaling devices such as are electrically actuated. The electrically-actuated 75 signals may be placed at street or railway grade-crossings along the line of track. The feed and branch wires may be supported upon the telegraph-poles along the right of way or 80 be otherwise disposed of. The current carried by the feed-wires F and G may be used for other services additional to that of actuating the signal system.

75

Many modifications of my invention may 85 be made without departing from its spirit.

Having thus described my invention, what I claim, and desire to secure by Letters Patent, is—

1. In a railway block-signal system, the combination with two feed-conductors, of means for creating an electric current in said conductors, the track-rails, opposite ones of which are divided into blocks insulated from each other, opposite rails of each block being adapted to be electrically connected through the intermediacy of the wheels and axles of cars supported thereon, branch conductors connecting respectively opposite rails of each block with opposite feed-conductors, and electrically-actuated signals disposed in some of the branch conductors of each block.

90

2. In a railway block-signal system, the combination with two feed-conductors, of means for creating an electric current in said conductors, the track-rails, opposite ones of which are divided into blocks insulated from each other, opposite rails of each block being adapted to be electrically connected through the intermediacy of the wheels and axles of cars supported thereon, branch conductors connecting respectively opposite rails of each block with opposite feed-conductors, and electric lamps inserted in some of the branch conductors of each block.

95

3. In a railway block-signal system, the combination with two feed-conductors, of means for creating therein an electric current, the track-rails, opposite ones of which are divided into blocks insulated from each other, opposite rails of each block being adapted to be electrically connected through the intermediacy of the wheels and axles of cars supported thereon, electrically-actuated signals disposed respectively adjacent the ends of each block, conductors connecting said signals with one

125

of the feed-conductors, conductors connecting one set of rails of each block with the signals in the next adjacent block, and conductors connecting the opposite rails of each block 5 with the other of the feed-conductors.

4. In a railway block-signal system, the combination with two feed-conductors, of means for creating therein an electric current, the track-rails, opposite ones of which are divided 10 into blocks insulated from each other, opposite rails of each block being adapted to be electrically connected through the intermediacy of the wheels and axles of cars supported thereon, electric lamps disposed respectively 15 adjacent the ends of each block, conductors connecting said lamps with one of the feed-conductors, conductors connecting one set of rails of each block with the lamps disposed in the next adjacent block, and conductors connecting 20 the opposite rails of each block with the other of said feed-conductors.

5. In a railway block-signal system, the combination with two feed-conductors, of means for creating an electric current in said conductors, the track-rails opposite ones of which are divided into blocks insulated from each other, opposite rails of each block being adapted to be electrically connected through the 25 intermediacy of the wheels and axles of cars supported thereon, electrically-actuated signals disposed respectively two adjacent each end of each block, one of each of said two signals being disposed nearer the adjacent end of the block in which it is located than the 30 other of the said two signals, conductors connecting said signals respectively with one of said feed-conductors, conductors connecting respectively one set of rails of each block with the adjacent signals of adjacent blocks, 35 and conductors connecting the opposite set of rails of each block with the other feed-conductor.

6. In a railway block-signal system, the combination with two feed-conductors, of means for creating an electric current in said conductors, the track-rails opposite ones of which are divided into blocks insulated from each other, opposite rails of each block being adapted to be electrically connected through the 40 intermediacy of the wheels and axles of cars supported thereon, electric lamps disposed respectively two adjacent each end of each block, one of each of said two lamps being disposed nearer the adjacent end of the block in which 45 it is located than the other of said two lamps, conductors connecting the said lamps respec-

tively with one of said feed-conductors, connecting respectively one set of rails of each block with the adjacent two lamps in the adjacent block, and conductors connecting the 60 opposite set of rails with the other feed-conductors.

7. In a railway block-signal system, the combination with two feed-conductors, of means for creating therein an electric current, the track-rails opposite ones of which are divided 65 into blocks insulated from each other, opposite rails of each block being adapted to be electrically connected through the intermediacy of the wheels and axles of cars supported thereon, electric lamps disposed two adjacent each end of each block the nearest two lamps of adjacent blocks being each invisible from the block next in advance of it, branch conductors connecting said lamps with one of 70 said feed-conductors, conductors connecting respectively one set of rails of each block with the adjacent two lamps in each block next adjacent thereto, conductors connecting respectively the opposite set of rails of each block 75 with the other feed-conductor, and a plurality of light-shields disposed one between each two lamps nearest the meeting-point of two blocks.

8. In a railway block-signal system the combination with two feed-conductors, of means for creating therein an electric current, the track-rails of the main line opposite ones of which are divided into blocks insulated from each other, conductors connecting one set of 80 rails of each block with one of said feed-conductors, branch conductors connecting the other sets of rails with the other feed-conductors, electric lamps disposed in each block and in each of said branch conductors, the track-rails of a switch one set of which connect with one set of rails in one block and the other set of rails of which connect with the opposite 85 set of the said block and cross the other set of rails in the same block, the crossing rail 90 of the switch being insulated from the rails at each end thereof, and a conductor connecting the rails at each end thereof around the insulated rail.

In testimony whereof I have signed my name 105 to this specification in the presence of two subscribing witnesses.

RECTOR E LAND.
